UNITED STATES PATENT OFFICE.

JAMES M. MOWATT AND ALEXANDER MOWATT, OF SPRINGFIELD, OHIO.

PROTECTOR FOR WOODWORKING-MACHINES.

SPECIFICATION forming part of Letters Patent No. 678,016, dated July 9, 1901.

Application filed January 2, 1901. Serial No. 41,758. (No model.)

To all whom it may concern:

Be it known that we, JAMES M. MOWATT and ALEXANDER MOWATT, citizens of the United States, residing at Springfield, county of Clark, 5 and State of Ohio, have invented a certain new and useful Improvement in Protectors for Woodworking-Machines, of which the following is a specification.

Our invention relates to a new and useful 10 improvement in protectors for woodworking-machines, and has for its object to provide a protector which will prevent the hands of the workman from being accidentally injured by the revolving cutters used in woodworking- 15 machines, such as frizzing-machines and the like.

With this end in view this invention consists in the details of construction and combination of elements hereinafter set forth 20 and then specifically designated by the claims.

In order that those skilled in the art to which this invention appertains may understand how to make and use the same, the construction and operation will now be described 25 in detail, referring to the accompanying drawings, forming a part of this specification, in which—

Figure 1 is a side elevation of our invention, showing in full lines the position it would 30 be placed in when the machine was operating, and dotted lines show the position it would take when it was pushed back, so as to leave the bits of the cutter accessible for sharpening or adjusting. Fig. 2 is a section taken 35 on the line 2 2 of Fig. 1, and Fig. 3 is a section taken on the line 3 3 of Fig. 1.

In carrying out our invention as here embodied, A represents a standard, which is composed of the upright member A' and the horizontal member A². This standard is secured 40 to the bed-plate of the machine by means of the foot A³, which is formed with the upright A'.

B is the protector, which consists of the 45 bell-shaped portion C. This bell C is open at its lower end and has the ring D secured to it by means of the lugs d, which are formed with the ring D, and the screw d', which passes through the lugs and is threaded into the 50 lower rim of the bell C. The ring D has a

circular opening in its center the same size as the diameter of the interior opening in the bell C. The upper end of the bell C has a hub E formed therewith which is interiorly threaded.

F is a threaded rod which has the eye G formed with it upon its upper end. This eye G is adapted to surround the horizontal member A² of the standard, so as to be adjusted along said horizontal member. The bell C is 60 suspended by means of the screw-rod F being threaded in the hub E of said bell. The horizontal member A² of the standard extends directly over the revolving cutters of the machine, and at a point on the horizontal member A² directly over the cutters a pin a is placed.

When it is desired to operate the machine, the eye G is slid along the member A² until the pin enters a cavity formed in the eye, 70 which will center the protector directly over the cutters. Then the set-screw H is screwed down, clamping the eye in place. The bell C and ring D are then screwed down the screw-rod F until the distance between the bed- 75 plate of the machine and the lower surface of the ring D is just sufficient to allow the work to pass therebetween. Then the bell C is clamped in that position by the nut I, which is also threaded on the screw-rod F and will 80 bind against the upper surface of the hub E. Then the material can be passed over the cutters and the work accomplished with as good results as without the protector, and the 85 hands of the operator could not be drawn into the cutters from any cause whatsoever. The bell C has the slots J formed therein, so that the workman can see through and observe the grain of wood he is working upon. The openings K, formed through the ring D, are 90 also for the same purpose.

When it is desired to sharpen or adjust the cutter or for another reason to have access thereto, the nut I is loosened and the protector B is screwed upward on the screw-rod 95 F, and if that does not give sufficient room the set-screw H can be loosened and the whole apparatus slid backward to the position shown in dotted lines in Fig. 1.

The rings D are easily removed from the 100

bell C by removing the screw d' , so that rings of larger diameter can be secured to the bell for larger work.

Of course we do not wish to be limited to the exact construction here shown, as slight modifications could be made without departing from the spirit of our invention.

Having thus fully described our invention, what we claim as new and useful is—

- 10 1. A protector for woodworking machinery consisting of a bell-shaped portion having a protecting-ring secured to its lower edge, a standard having a horizontal member extending directly over the cutters of the machine, a screw-rod adapted to slide along the horizontal member of the standard, the bell-shaped portion and ring adapted to be suspended by and adjustable upon said screw-rod, means located upon the horizontal member of the standard for stopping and centering the movable members of the protector directly over the cutters, substantially as described and for the purpose specified.
- 15 2. In combination with an apparatus of the character described, a standard secured to the bed-plate of the machine and having a horizontal member extending directly over the cutters of the machine, a screw-rod suspended from said horizontal member along which said screw-rod is adapted to be adjusted, means for centering and clamping said screw-rod in place upon the horizontal member, a shield threaded upon said screw-rod so as to be suspended by and adjusted vertically thereupon, consisting of a bell-shaped portion and a removable protecting-ring secured to the lower end of the bell, openings formed through the bell-shaped portion and the ring, and a lock-nut also threaded upon the screw-

rod F for the purpose of clamping the shield 40 in place, substantially as described and for the purpose specified.

3. In combination with an apparatus of the character described, a standard secured to the bed-plate of the machine having a horizontal member A² extending directly over the cutters of the machine, a screw-rod F suspended from said horizontal member A² by means of the eye G formed with said screw-rod through which the horizontal member A² 45 protrudes, a pin a formed upon the horizontal member A² adapted to register with and enter a cavity in the eye G for the purpose of stopping and centering the screw-rod directly over the cutters, a set-screw adapted to 50 clamp the eye G in place upon the horizontal member A², a shield B consisting of the bell-shaped portion C adapted to be threaded upon the screw-rod F, and a flat ring D removably secured to the lower end of the bell-shaped 55 portion C, openings J formed through the walls of the bell-shaped portion C, openings K formed through that portion of the ring which lies outside of the bell-shaped portion C, and a lock-nut threaded upon the screw-rod F and adapted to be bound against the bell-shaped portion C for the purpose of clamping the same in place, substantially as described and for the purpose specified.

In testimony whereof we have hereunto affixed our signatures in the presence of two subscribing witnesses.

JAMES M. MOWATT.
ALEXANDER MOWATT.
